(57) **CLAIM**

The ornamental design for a handle for a portable sprayer, as shown and described.

DESCRIPTION

FIG. 1 is a perspective view of our new design for a handle for a portable sprayer;

FIG. 2 is a right side elevation view thereof;

FIG. 3 is a left side elevation view thereof;

FIG. 4 is a rear elevation view thereof; and,

FIG. 5 is a top plan view thereof.

The broken line portion of the sprayer housing in FIGS. 1-5 is for illustrative purposes only and forms no part of the claimed invention.
